DESIGN FOR A SIGN STANDARD

Arthur J. Coon, Providence, R. I.

Application May 15, 1933. Serial No. 48,123

Term of patent 7 years

To all whom it may concern:

Be it known that I, ARTHUR J. COON, a citizen of the United States of America, residing in Providence, county of Providence, State of Rhode Island, have invented a new, original, and ornamental Design for a Sign Standard, of which the following is a specification, reference being had to the accompanying drawing forming a part thereof.

Fig. 1 is a front elevational view of a sign standard, showing my new design; and Fig. 2 is a side elevation of the same.

I claim:

The ornamental design for a sign standard, substantially as shown.

ARTHUR J. COON.
